US00D773505S

(12) **United States Design Patent** (10) Patent No.: **US D773,505 S**
Knapp (45) Date of Patent: ** Dec. 6, 2016

(54) **DISPLAY SCREEN WITH GRAPHICAL USER INTERFACE**

(71) Applicant: **Microsoft Corporation**, Seattle, WA (US)

(72) Inventor: **Jaclyn Carley Knapp**, Redmond, WA (US)

(73) Assignee: **Microsoft Corporation**, Redmond, WA (US)

(**) Term: **14 Years**

(21) Appl. No.: **29/503,829**

(22) Filed: **Sep. 30, 2014**

(51) LOC (10) Cl. **14-04**

(52) U.S. Cl.

USPC **D14/486**

(58) **Field of Classification Search**

USPC **D14/485-495**

(57) **CLAIM**

The ornamental design for a display screen with graphical user interface, as shown and described.

DESCRIPTION

The FIGURE is a front view of a display screen with graphical user interface showing my new design. The broken line showing the remainder of the graphical user interface and the remainder of the display screen forms no part of the claimed design.

1 Claim, 1 Drawing Sheet
